TWO-STROKE INTERNAL COMBUSTION
ENGINE

Alfred Bokemüller, Gaggenau-Baden, Germany,
assignor, by mesne assignments, to Sir W. G.
Armstrong Whitworth & Co. (Engineers) Lim-
ited, Newcastle-upon-Tyne, England

Application July 8, 1936, Serial No. 89,538
In Germany July 8, 1935

4 Claims. (Cl. 123—65)

The present invention relates to improved means for and method of engine control and, more particularly, to the control of the inlet and/or outlet passages of an internal combustion engine. While the invention is adapted for use with any type of internal combustion engine, it is of particular significance in connection with a two-stroke engine of the so-called "Diesel" type.

An object of this invention is the provision of means for obtaining improved operation and efficiency of an internal combustion engine.

Another object of this invention is the provision of means for obtaining effective and reliable scavenging of the cylinder or cylinders of an internal combustion engine.

Still another object of this invention is the provision of improved valve and valve seat for an internal combustion engine.

A further object of this invention is the provision of an improved method for effectively scavenging the cylinders of an internal combustion engine.

With the foregoing and other objects in view which will appear as the description proceeds, the invention resides in the combination and arrangement of parts and in the details of construction hereinafter described and claimed.

The invention is illustrated diagrammatically and by way of example on the accompanying drawing on which:

Figure 1 is an axial section of the cylinder and the piston and some adjacent parts of a two-stroke Diesel-engine, the outlet-passage of which is controlled by the piston;

Figures 2 and 3 show each a portion of the valve disk and the adjacent portion of the seat therefor, figures drawn to a greatly enlarged scale relatively to Fig. 1;

Figure 4 shows details of Fig. 3, the scale being still larger.

Figure 5 shows an explanatory diagram; and

Figure 6 is a view similar to Fig. 1 showing a modified construction.

Referring to Fig. 1, 1 denotes the cover of the cylinder, 2 denotes a cooling chamber in said cover, and 3 an inlet passage, at the inner end of which is located a disk-valve 4, the bottom-surface 5 of which constitutes the top of a combustion space 6 located axially in the cover 1. A communicating fuel supply channel 7 is likewise provided in said cover and may extend radially with respect to the axis of the cylinder and somewhat obliquely, as shown. For best operation it is important that the inlet passage is as short as possible and leads directly into the open air.

With special regard to the valve disk and its seat, besides the usual conical seat 8, the latter is provided with a collar-like additional seating surface 9 (Figs. 2, 3 and 4) which co-operates with the rim zone 9^a of the valve disk. In accordance with the length of the tightening surfaces 9, 9^a, the valve 4 will be opened earlier or later, but always only after the valve disk 5 has covered the path a (Fig. 4). This path a in Fig. 4 corresponds with the path a in the diagram shown in Fig. 5. From the curve I in this figure, it appears that the cam shaft has turned during that time through a crank-angle of 20° (from 100+80), and when then the opening of the valve passage commences at the point A the disk of the valve has already attained a considerable speed and in the period of time t it will cover the path b.

The advantage which this operating valve presents for a two-stroke engine operating after the oscillation principle become quite obvious if it is compared with the commencement of the stroke curve II indicated by a dotted line in Fig. 5. In the same section of time t the valve only covers the path c. Similar are the conditions when the valve is being closed (point B of the curve I in Fig. 5). The valve is closed with a considerable speed and its passage is already blocked before the speed of the closing movement of the valve disk 5 has become considerably lower.

Referring again to Fig. 1, 10 denotes the outlet of the machine and 11 denotes the working piston of the same. The inlet valve 4 is so controlled that it opens a predetermined time after the outlet slots have been uncovered by the piston, and a waste gas column of high velocity has arisen in the outlet pipe, producing a vacuum as high as possible in the cylinder. Furthermore, the outlet pipe has such dimensions, particularly such a length, that a return of a portion of the gas column cannot hinder the scavenging air from entering into the cylinder. The necessary dimensions can readily be found by experiment. As shown in Fig. 1, a suitable device 10a may be provided in the outlet pipe 10 which is so constructed as to partially prevent the return of gas into the cylinder. As can readily be seen, the device 10a allows almost totally unobstructed flow of the gases from the cylinder to the outer portion of the outlet pipe but will tend to catch and obstruct the passage of such gases when returning to the cylinder.

Owing to the arrangement of the valve in the manner shown and described, the unreliable and variable portions of gas movement at the com-

mencement and at the end of the valve movement are dispensed with. This is another advantage which this invention presents to which may be added the further advantage that the valve disk 5 forms together with the valve of the wall aperture a nozzle-like passage 12, viz., a passage having a nozzle-like sectional area which may well be utilized for a thorough dispersion or atomization of the fuel as it passes into the combustion 10 chamber.

I wish to be understood that I consider it as lying within the scope of my invention if the combustion space 6 and the channel 7 are provided at another suitable place in the cylinder 15 head or at the cylinder, and the shape of said parts of the engine may be quite as desired. Instead of an injection nozzle an incandescence body, a spark plug or the like may be provided, the fact being that the invention can be used in 20 connection with internal combustion engines of all constructional forms in which the entrance of the scavenging air and of the combustion air is effected or assisted by the sucking action of the escaping exhaust gases.

25 In this respect, by way of example I refer especially to Fig. 6 in which is represented a two-stroke internal combustion engine having an inlet valve 13 and an outlet valve 14 in the cylinder head. Also in this example the inlet passage 15 is as short as possible and communicates directly with the open air, whereas the outlet passage 16 30 communicates with a nozzle-like exhaust pipe 17.

35 While I have herein shown and described only certain embodiments of certain features of my present invention it is to be understood that they are to be regarded merely as illustrative and that I do not intend to limit myself thereto except as may be required by the following claims.

I claim:

40 1. In a two-stroke cycle internal combustion engine, in combination, a cylinder provided with an exhaust orifice, means for opening said exhaust orifice to permit the burnt gases to be discharged from the cylinder at high velocity and as a mass, leaving a high depression behind them, an inlet passage communicating with the cylinder, a valve adapted to open and close said inlet passage, comprising a disk, and a seating surface therefor positioned transversely with respect to the direction of motion of said disk, said seating surface having a portion extending parallel to the direction of motion of said disk, whereby said valve opens only after said disk has travelled a predetermined distance, and means for opening said inlet valve when the said depression has been created and a suction effect is exerted at the inlet orifice.

45 2. In a two-stroke cycle internal combustion

5 engine, in combination, a cylinder provided with an exhaust orifice, a valve adapted to open and close said orifice said valve comprising a disk, and a seating surface therefor positioned transversely with respect to the direction of motion of said disk, said seating surface having a portion extending parallel to the direction of motion of said disk, whereby said valve opens only after said disk has travelled a predetermined distance, means for opening said exhaust valve 10 to permit the burnt gases to be discharged from the cylinder at high velocity and as a mass, leaving a high depression behind them, an inlet passage communicating with the cylinder, a valve adapted to open and close said inlet passage, and means for opening said inlet valve when the said depression has been created and a suction effect is exerted at the inlet orifice.

3. In a two-stroke cycle internal combustion engine, in combination, a cylinder provided with an exhaust orifice, a valve adapted to open and close said orifice, means for opening said exhaust valve to permit the burnt gases to be discharged from the cylinder at high velocity and as a mass, leaving a high depression behind them, an inlet passage communicating with the cylinder, a valve adapted to open and close said inlet passage, and means for opening said inlet valve when the said depression has been created and a suction effect is exerted at the inlet orifice, 20 each of said valves comprising a disk, and a seating surface therefor positioned transversely with respect to the direction of motion of said disk, said seating surface having a portion extending parallel to the direction of motion of said disk, 25 whereby said valve opens only after said disk has travelled a predetermined distance.

4. In a two-stroke cycle internal combustion engine in combination, a cylinder provided with an exhaust orifice, means for opening said exhaust orifice to permit the burnt gases to be discharged from the cylinder at high velocity and as a mass, leaving a high depression behind them, an inlet passage communicating directly with the atmosphere and with the cylinder, a valve adapted to open and close said inlet passage, comprising a disk, and a seating surface therefor positioned transversely with respect to the direction of motion of said disk, said seating surface having a portion extending parallel to the direction of motion of said disk, whereby said valve opens only after said disk has travelled a predetermined distance, and means for opening said inlet valve when the said depression has been created and a suction effect is exerted at 50 the inlet orifice.

ALFRED BOKEMÜLLER.
